The United States of America.

TO ALL TO WHOM THESE Letters Patent SHALL COME:

Whereas Enoch Walker, a citizen of the United States, hath alleged that he has invented a new and useful improvement in the Panelling, &c.

which improvement he states has not been known or used before his application, hath affirmed that he does verily believe that he is the true inventor or discoverer of the said improvement, hath paid into the treasury of the United States the sum of thirty dollars, delivered a receipt for the same, and presented a petition to the Secretary of State, signifying a desire of obtaining an exclusive property in the said improvement, and praying that a patent may be granted for that purpose. These are therefore to grant, according to law, to the said Enoch Walker, his heirs, administrators or assigns, for the term of fourteen years, from the twentieth day of September, one thousand eight hundred and twenty six, the full and exclusive right and liberty of making, constructing, using and vending to others to be used, the said improvement, a description whereof is given in the words of the said Enoch Walker himself, in the schedule hereto annexed, and is made a part of these presents.

In Testimony whereof, I have caused these Letters to be made Patent, and the Seal of the United States to be hereunto affixed.

GIVEN under my hand, at the City of Washington, this twentieth day of September, in the year of our Lord one thousand eight hundred and twenty six, and of the independence of the United States of America the fifth year.

J. Q. Adams.

BY THE PRESIDENT.

W. H. Secretary of State.

City of Washington, To Wit:

I DO HEREBY CERTIFY, That the foregoing Letters Patent were delivered to me on the ~~20th~~ day of ~~September~~ in the year of our Lord one thousand eight hundred and twenty six, to be examined; that I have examined the same, and find them conformable to law; and I do hereby return the same to the Secretary of State, within fifteen days from the date aforesaid, to wit, on this ~~20th~~ day of ~~September~~ in the year aforesaid.

W. W. Attorney General of the United States.

W. J. Smith, Sc. Wm. C.

The Schedule referred to in these Letters Patent®
making part of the same, containing a description in the words of the
said Enoch Walker, himself, of his improvement in the Framing
Mill, -

Each side of mill is made by nailing or screwing two boards about 24 inches wide cross-ways. The upright one about four feet high, its lower end resting on the floor, and the horizontal one about 4 $\frac{1}{4}$ feet long, its upper edge about five inches from the top of the upright one - one end extending over the edge of the upright board, above a foot, to be rounded or angled for fan cover, to extend round the outside, under & upwards, and down inner sides as long as the cog-shaft, to bring the wind to a focus to act where it should, let the fan turn which way it may; - secure those sides of the mill in their places (with the fan-shaft about thirty one inches from the floor & the cog-shaft through the body of the mill about 8 6 inches, also from the floor, & in his mills of common size & form about 16 inches from the fan-shaft,) by nailing or screwing four boards rabbeded to the edges of the upright boards, the two upper ones about five inches wide, and the two lower ones about ten inches wide and each of them about two feet long, according to the width of the mill. - In the middle of said shaft passing through the body of the mill there are about four cogs or points
to.

to shake the whole bottom of the hopper like an inclined plane placed in a long motion over the wings where preferred, to cast the grain through teeth like a fork or any part of the sieve preferred, - or make the whole hopper like a bottling shoe of a gist mill with the teeth attached to its lower end to shake up the straw & chaff over & through the wind whilst the grain falls about six inches, or more, on & through the sieve; this width - the outlet of the hopper & screen board to convey away the grain, as wide or nearly as the mill, working up and down and end ways by motion of said cage as otherwise. - The wire of the sieve is nailed to the lower edges of side boards and strips for their inner and outer ends. The middle of their inner ends are attached where best to a perpendicular spring from said cage down through the means of the screw to a short board, into the middle of a strong bolt through the mill near the floor, with a spring lever in its outer end with a catch to hold the top of the spring, (to which the sieve are attached) to said cage and give a free motion to the sieve & screen board, all suspended with about three cleats of about twenty inches long; two of them just inner side of tail end of mill, with holes in their lower ends for points in the outer ends of the sides of the sieve, and upper end of screen board to hook in at any angle to work free without any obstruction above the sieve as common mills to the straw and chaff passing freely away.

The

The lower end of the middle of the screw board (which has strips on its edges to prevent the grain falling over the sides, is suspended with said strips as aforesaid, attach'd to the fan cover above, or any other way preferred. Work the mill with friction wheels (or cog or band wheels as common) with a handle near the edge of the large one, on the end of said cog shaft, the man turning standing by the side of the hopper to regulate the feed without another person - place a bolt longer than the mill is wide near the lower outer corners of said horizontal or cross boards to secure the tail board higher or lower at any angle by keeping the tail ends of the cross boards in their places to the ends of said tail board, by a screw or key to the end of said bolt - -

These improvements may be applied in part or altogether to ~~the old common fence mill~~ the mill, and it will be an improvement that will answer.

Place boards ~~so~~ ~~that~~ ~~the~~ ~~inner~~ ~~sides~~ ~~of~~ ~~the~~ ~~mill~~ ~~above~~ ~~the~~ ~~edges~~ ~~of~~ ~~the~~ ~~sides~~ ~~of~~ ~~the~~ ~~screws~~ ~~prevent~~ ~~grain~~ ~~from~~ ~~falling~~ ~~over~~ ~~the~~ ~~outer~~ ~~sides~~ ~~and~~ ~~no~~ ~~hopper~~ ~~like~~ ~~a~~ ~~hutting~~ ~~as~~ ~~aforsaid~~, ~~but~~ ~~strips~~ ~~of~~ ~~leather~~ ~~or~~ ~~cloth~~ ~~the~~ ~~inner~~ ~~sides~~ ~~of~~ ~~the~~ ~~hopper~~ ~~being~~ ~~the~~ ~~upper~~ ~~ends~~ ~~of~~ ~~the~~ ~~upright~~ ~~boards~~ ~~as~~ ~~aforsaid~~, ~~to~~ ~~prevent~~ ~~grain~~ ~~expansions~~ ~~through~~ ~~between~~ ~~the~~ ~~edges~~ ~~of~~ ~~the~~ ~~bottom~~ ~~of~~ ~~the~~ ~~hopper~~ ~~or~~ ~~inclined~~ ~~plane~~ ~~work~~ ~~as~~ ~~aforsaid~~ ~~as~~ ~~a~~ ~~thin~~ ~~piece~~ ~~to~~ ~~the~~ ~~lower~~ ~~ends~~ ~~of~~ ~~said~~ ~~upright~~ ~~boards~~, ~~to~~ ~~make~~ ~~or~~ ~~longer~~ ~~bearing~~ ~~on~~ ~~the~~ ~~floor~~ ~~&~~ ~~strengthening~~ ~~the~~ ~~mill~~.

One applying said improvements to the common windmill removes the ~~hoppers~~

hoppers etc. etc. within, including the common shoe, and place the egg shaft
to work as aforesaid, as close to the common wings as will answer, & about
seven inches lower than level with the top of the wings over which place
the bottom of the hopper as aforesaid, with the sieves & screen board as wide
or nearly as the mill to work as aforesaid or any other way preferred
with the outlet of the hopper as wide or nearly as the mill. --
